CLAIM

The ornamental design for a portable mail slot chute with cleat and thumb grip for mail carrier, as shown and described.

DESCRIPTION

FIG. 1 is a perspective view of the portable mail slot chute with cleat and thumb grip for mail carrier embodying the design of the present invention;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof;

FIG. 6 is a bottom plan view thereof; and,

FIG. 7 is a side elevational view showing the portable mail slot chute with cleat and thumb grip for mail carrier in use; the broken lines depict environmental structure and form no part of the claimed design.
